SAFETY-VALVE.

1,380,094.

Specification of Letters Patent. Patented May 31, 1921.

Application filed March 30, 1920. Serial No. 369,951.

To all whom it may concern:

Be it known that I, GEORGE HALL CLARK, a citizen of the United States, and resident of Melrose, in the county of Middlesex and 5 State of Massachusetts, have invented new and useful Improvements in Safety-Valves, of which the following is a specification.

My invention relates to that class of safety valves which is characterized by a single 10 valve disk seating upon concentric seats, and has for its main object the provision of effective and convenient means for adjusting the controller which by progressively constricting the effective area of egress apertures leading from the inner of the concentric valve seats as the valve disk rises and, 15 reversely, progressively enlarging the said effective area as the valve disk subsides, affords control of the lift and subsidence of 20 the valve disk. Other structural advantages will transpire from the description of my improved valve which follows.

In the prevailing single seated type of safety valve, it has been observed that these 25 valves have a considerably lower sustained lift at popping pressure than the lift to which they rise momentarily at the pop, and that the difference between these two degrees of lift is greater than the increase in sustained lift gained by the standard permissible 30 3% accumulation. Lifting means employed to assist such a valve during its accumulation period will necessarily be active at the pop, and the valve will immediately 35 pop into its high lift, for, if the lifting means does not become active at the moment of pop, a 3% accumulation will not suffice to bring it into action. With a double seated valve, however, the egress apertures from 40 one of the concentric valve seats may be employed with suitable controlling means so that the effective area of such egress apertures shall be progressively constricted as the valve disk rises to predetermined points 45 of lift; thus effectiveness of control may keep pace with changing conditions and is a powerful factor when control is most needed.

The predetermination of the behavior of a 50 valve disk depends on adjustment of the initial effective cross section of control aperture, and also on the rate at which this area is diminished as the valve disk rises, and on the relation between these two factors. Nice regulation requires accurate and easily manipulated adjusting devices, and these are

provided by the improved valve structure herein described.

The drawing hereto annexed illustrates a safety valve, in vertical cross section, in which my improvement is embodied.

The safety valve illustrated in this drawing is provided with the usual means for attachment to the boiler shell or the like and with other adjuncts which being well known will not require description.

The operating members of the safety valve comprise a base B on which concentric valve seats are formed at S and S', and a valve disk D normally held in engagement with the said valve seats by the adjustable 70 spring G which is housed in the hood M of the valve casing. The base B has formed in its body a well W which has a closed bottom and is centrally located in the base and the valve disk D carries a tubular member T of 75 which the interior space T' is open at both top and bottom communicating at the top with the egress passage E which terminates in discharge apertures E' in the outer periphery of the valve disk D. The tubular 80 member T is provided with a number of apertures A all of which are adjacent to the valve seat S' when the valve disk is in closed position. A sleeve R threaded into the lower end of the hood M makes a sliding fit with 85 the outer periphery of the disk D and the lower lip of the said sleeve may be made to cover more or less of the egress apertures E' according as the sleeve R is screwed down or up in relation to the seating valve disk. 90 In order to provide easy access to the disk D for purposes of adjustment and regulation the screw plug P' carrying the retaining pin P is threaded into the valve casing from which it may be removed together with the 95 pin P whenever it is desired to change the adjustment of the regulating sleeve R. The sleeve R is provided at intervals on its periphery with lugs R' which serve as holds for a suitable instrument inserted through the threaded aperture through which the plug P' has been removed and which lugs also engage with the pin P to retain the 100 said regulating disk in any position to which it has been adjusted.

When the steam pressure resisted by the spring G has reached a predetermined value the valve disk D is started from its seat and when lifted a short distance the apertures A are uncovered and steam passing through 110

them enters the tubular interior T' of the member T producing therein an auxiliary lifting pressure which assists in lifting the disk D. The measure of this auxiliary lifting force depends on the freedom with which steam is permitted to escape through the egress apertures E'. If it be desired to make this initial lifting pressure considerable so as to overcome the resistance of the spring G and produce an immediate increase of lift of the disk the regulating sleeve R should be adjusted downwardly so as to produce an initial restriction of the egress apertures E'. Such an adjustment of the regulating sleeve provided the apertures E' are circular in cross section would also produce a relatively rapid rate of further constriction of the egress apertures as the valve disk rises and the disk will therefore immediately assume and maintain its predetermined high lift and will do so without first jumping to a relatively high position of pop lift and afterward subsiding to a position of sustained lift. Conversely the initial auxiliary lifting pressure may be reduced by an upward adjustment of the regulating sleeve R.

The regulating sleeve by reason of its screw threaded relation with the valve bonnet M is susceptible of very nice adjustment and with the features above described which are characteristic of the two-seated type of valve provides an accurate instrument of regulation so that within the extreme limits of its susceptibility to lift-adjustment any degree of sustained lift may be obtained. As boiler pressure subsides the progressive

increase of effective area of the egress apertures E' diminishes the total lifting pressure on the under side of the valve disk in a reverse progression and insures prompt closure of the valve with a minimum of blow down.

I claim:

1. In a safety valve, a base provided with concentric seats, and a central well, a valve disk seating on both inner and outer seats, and provided with a tubular portion slidably mounted in said central well, apertures between the interior of said tubular portion and the inner valve-seat, an egress conduit from said tubular portion having its discharge opening from the valve disk outside the outer valve seat; a sleeve, adjustably mounted in the valve casing, making a sliding fit with the outer periphery of the disk and coacting with said egress conduit to constrict the effective aperture thereof as the valve disk rises.

2. In a safety valve, a base provided with concentric valve-seats, a valve disk seating on both inner and outer seats, and provided with a passage from its central portion within the inner valve seat to its periphery beyond the outer valve seat, and a sleeve adjustably mounted in the valve casing, making a sliding fit with the outer periphery of the disk, and coacting with the peripheral terminus of said passage in the valve, to constrict the effective egress aperture thereof as the valve disk rises.

Signed by me at Boston, Massachusetts, this 23rd day of March, 1920.

GEORGE H. CLARK.
